UNITED STATES PATENT OFFICE.

FREDERICK C. BAKER, OF PORTLAND, OREGON.

DESIGN FOR AN ELECTRIC-LIGHT WALL-BRACKET FIXTURE.

48,513.

Specification for Design.

Patented Feb. 8, 1916.

Application filed February 26, 1915. Serial No. 10,875. Term of patent 7 years.

To all whom it may concern:

Be it known that I, FREDERICK C. BAKER, a citizen of the United States, residing at Portland, in the county of Multnomah and State of Oregon, have invented a new, original, and ornamental Design for an Electric-Light Wall-Bracket Fixture, of which the following is a specification, reference being had to the accompanying drawing, forming a part hereof.

Figure 1 is a bottom plan view; Fig. 2 is

a side elevation of my ornamental design, and Fig. 3 is a front elevation of my ornamental design.

I claim:

The ornamental design for an electric light wall bracket fixture, substantially as shown.

F. C. BAKER.
